ADJUSTABLE SUPPORT FOR DOORS

James A. Crabtree, 391 SW. Forest Drive,
Issaquah, Wash. 98027

Filed Dec. 9, 1974, Ser. No. 536,918

Term of patent 14 years

Int. Cl. D25—99

FIG. 1 is a right front perspective view of an adjustable support for doors embodying my new design.

FIG. 2 is a left front perspective view.

FIG. 3 is a front elevational view.

I claim:

The ornamental design for an adjustable support for doors, substantially as shown.
